Specification for Design.

Patented Aug. 20, 1912.

Application filed June 26, 1911. Serial No. 635,484. Term of patent 14 years.

● *To all whom it may concern:*

Be it known that I, JACOB A. ENGEL, a citizen of the United States, residing at the city of Syracuse, in the county of Onondaga, State of New York, have invented a new, original, and ornamental Design for Hose-Display Brackets, of which the following is a specification, reference being had to the accompanying drawing, forming a part thereof.

The figure in the drawing is an isometric view of the bracket showing my design

which consists of a cylindrical base —a— having a downwardly extending arm —b—, the intermediate portion of said arm being provided with beads *c—c* as shown.

What I claim is:

The design for a hose display bracket as shown and described.

JACOB A. ENGEL.
